BERNARD ROUS, OF BROOKLYN, NEW YORK

DUPLEX ROLL OF CORRUGATED PAPER AND METHOD AND MEANS FOR MAKING
THE SAME

Application filed July 5, 1929. Serial No. 376,091.

The invention relates to a duplex roll of corrugated paper and method and means for manufacturing such roll.

The well known form of corrugated paper which comprises a corrugated sheet and a single facing glued together is manufactured and shipped in large rolls. While these rolls are comparatively light in weight, they are extremely bulky and occupy much space, making the transportation costs high in proportion to the value of the roll. Moreover, concerns using a substantial amount of corrugated paper are forced to devote a large space for storage of the rolls because of their bulkiness.

In the roll of corrugated paper as manufactured at the present time the corrugated sheet and facing sheet are secured together and are wound on a mandrel. Naturally the corrugated sheet occupies a great part of the space in the roll and causes the roll to be large regardless of how tightly it may be wound. It is proposed under the present invention to utilize part of this space by winding into the roll another corrugated sheet and facing sheet, likewise glued together, thus forming a duplex roll.

The advantage of this novel departure is that a roll of corrugated paper is produced which contains almost double the amount of the single roll and occupies substantially the same space in transportation and storage.

Further objects and advantages will become apparent as the specification proceeds. Referring to the drawings forming a part hereof:

Fig. 1 is a perspective view of a duplex roll of corrugated paper made in accordance with the invention. In this view the roll is shown as being partly unwound so as to clearly illustrate the two sheets of corrugated paper;

Fig. 2 is a fragmentary detail sectional view through part of the roll; and

Fig. 3 is a schematic sectional view showing a means for manufacturing the duplex roll.

Referring again to the said drawings, and particularly to Figs. 1 and 2, the reference numeral 2 designates the duplex roll of corrugated paper. The roll is made up of two complete sheets or webs of corrugated paper.

One of these consists of the corrugated sheet 3 and the facing sheet 5 united together in the usual manner. The other consists of the corrugated sheet 4 and the facing sheet 6 likewise united together.

In the roll the facing sheets 5 and 6 lie next each other and are tightly wound in relation to each other. The corrugated sheets 3 and 4 are intimately associated so that their corrugations rest within each other. Nevertheless, when the roll is unwound as indicated in Fig. 1 the two corrugated sheets readily separate and fall away from each other. It will be apparent from an inspection of Figs. 1 and 2 that the duplex roll of corrugated paper will contain almost double the amount of the ordinary single roll.

It is important in the manufacture of the product to corrugate the two sheets at the same time so that they may be caused to nest with each other and to maintain this intimate relation while the facing sheets are being applied and until the duplex roll has been wound.

An apparatus for manufacturing the duplex roll of corrugated paper is diagrammatically illustrated in Fig. 3.

Two webs of paper 7 and 8 which later form the corrugated sheets 3 and 4 are suitably supported and are fed over a corrugating roller 9. The corrugating roller 9 meshes with another corrugating roller 10 and as the sheets from the webs 7 and 8 pass between the pair of corrugating rollers 9 and 10 they are corrugated and intimately associated. Any well known means may be provided for rotating the corrugating rollers.

Because the two sheets are corrugated simultaneously this intimate relation is insured. This is an important feature of the invention, since it would be practically impossible to form the two sheets separately and match up the corrugations afterwards, due to the varying diameters of the roll.

After the sheets have been simultaneously corrugated an adhesive is applied to the outer corrugated sheet 3. A roller 11 rotates in a glue well 12 and transfers the adhesive to another roller 13, which in turn transfers it

to the sheet 3. Guide fingers 14 lying in slots of the roller 13 allow the corrugated sheets to fall away slightly from the corrugating roller 10 and contact with the periphery of the roller 13.

Means are provided in conjunction with the corrugating rollers for introducing the facing sheet 5 and causing it to be secured to the corrugated sheet 3 by the adhesive supplied by roller 13. The facing sheet 5 is fed from a web 15 over guide rollers 16 and 17 and under a pressure roller 18, which presses the facing sheet 5 against its corrugated sheet 3, so as to insure the adhesive holding it there.

It is important that the two corrugated sheets be maintained in their intimate relationship until they are later wound on the completed duplex roll. After leaving the corrugating roller 10 and pressure roll 18, the corrugated sheets 3 and 4 and facing sheet 5 pass over curved guide members 19. The guide members 19 might be in the form of rods, or if desired a plate could be used. The guide members are so curved that the corrugated sheets ride on the convex side with the facing sheet 5 outermost. A sufficient tension is thus maintained to insure the corrugated sheets remaining undisturbed.

After leaving the guide members 19, the sheets pass over a roller 20, and thence over other guide members 21, which are also curved in the same manner and for the same reasons as guide members 19. The guide members 21 have extensions 22 beyond a guide roller 23.

The adhesive is applied to the corrugated sheet 4 in the region beyond the roller 23. A roller 24 is rotatably mounted in the glue well 25. This roller 24 transfers the glue to another roller 26, which in turn transfers it to the sheet 4. The extensions 22, which are in the form of blades, rest in slots or cut-out portions of the roller 26.

Pivoted at 27 to the blades 22 are fingers 28, which act as supports for the sheets until they reach the winding mandrel or shaft 29. The fingers 28 are pivoted so as to function as supports for the sheets while the diameter of the completed roll is increasing on the mandrel 29.

The facing sheet 6 is preferably secured to the corrugated sheet 4 in conjunction with the winding of the roll. This facing sheet 6 passes from a web roll 30 over guide rollers 31 and 32 and thence over a pressure roll 33, which causes the adhesive applied by roller 26 to hold the facing sheet 6 and corrugated sheet 4 together. The adhesive is given a further chance to set by reason of the stretch caused by the facing sheet 6 being wound on the outside of the roll.

As the diameter of the duplex roll increases on the mandrel 29, the pressure roller 33

moves outward. A weight or weights 35 on cables or chains secured to the pressure roll trunnions and passing over rollers 36 insures an even pressure being exerted by the roller 33 at all times regardless of the diameter of the roll being wound on the mandrel 29.

In order to cause the facing sheet 6 to be led in in proper relation to the duplex roll as the latter increases in diameter, the pressure roll 33 and guide roller 32 are mounted on arms 37 pivoted in bearings at the ends of the guide roller 31.

The fingers 28 are connected together by a rod 38, so as to keep them from being displaced laterally and coming in contact with the adhesive applied by roller 26. The rod 38 has a slotted connection 39 with the arm 37. Thus, the weight 35 will act to maintain the fingers in their proper relation to the sheets and the duplex roll as it is being wound.

Numerous changes may be made in details of construction and arrangements of parts in the aforesaid apparatus for manufacturing the duplex roll of corrugated paper, and all such changes are to be construed as coming within the scope of the appended claims.

I claim:

1. A duplex roll of single-faced corrugated paper, each part of which comprises a facing sheet and a corrugated sheet secured together, the facing sheets lying smoothly adjacent each other in said roll and the corrugated sheets being intimately associated and separable.

2. Means for manufacturing a duplex roll of corrugated paper comprising in combination, means for corrugating and intimately associating two sheets of paper, means for securing facing sheets to the respective corrugated sheets, and means for winding the two corrugated and faced sheets into a duplex nested roll, the means for associating the facing sheet which is outermost in the convolutions of the duplex roll operating in conjunction with the winding means.

3. Means for manufacturing a duplex roll of corrugated paper comprising in combination, a pair of corrugating rollers for corrugating and intimately associating two sheets of paper, means operating in conjunction with said corrugating rollers for introducing and securing a facing sheet to one of said corrugated sheets, means for winding the duplex roll of paper, and means in conjunction with said winding means for introducing and securing a facing sheet to the other corrugated sheet.

4. Means for manufacturing a duplex roll of corrugated paper having in combination, a pair of corrugating rollers for corrugating and intimately associating two separate sheets of paper, means for applying adhesive to one of said corrugated sheets, means for

introducing a facing sheet so that it will be secured to said corrugated sheet by said adhesive, means for applying adhesive to the other of said corrugated sheets, means for introducing and securing to said second-mentioned corrugated sheet by said adhesive another facing sheet at the same time that the sheets are wound into a roll, and means for closely winding all said sheets into a duplex roll.

5. Means for manufacturing a duplex roll of corrugated paper comprising in combination, a pair of corrugating rollers for corrugating and intimately associating two sheets 15 of paper, means operating in conjunction with said corrugating rollers for introducing and securing a facing sheet to one of said corrugated sheets, means for winding said duplex roll, means in conjunction with said 20 winding means for introducing and securing a facing sheet to the other of said corrugated sheets, and means for maintaining the intimate relation of said corrugated sheets in their travel from the corrugating 25 rollers to the winding means.

6. The method of manufacturing a duplex roll of corrugated paper, which comprises supplying two sheets of paper and corrugating them together, supplying a facing 30 sheet and applying it to one of the corrugated sheets, supplying another facing sheet and applying it to the other corrugated sheet at the same time that the sheets are wound into a roll, and winding the sheets upon the 35 roll.

7. The method of manufacturing a duplex roll of corrugated paper, which comprises supplying two sheets of paper and corrugating them together, applying adhesive to 40 the outer side of one of the corrugated sheets, supplying a facing sheet and causing it to adhere to this corrugated sheet, applying adhesive to the outer side of the other corrugated sheet, introducing another facing sheet 45 and attaching it to the latter corrugated sheet at the same time that all the sheets are wound into a roll, and winding the sheets upon the roll.

BERNARD ROUS.
